LOUIS M. POTTS, OF EVANSTON, ILLINOIS, ASSIGNOR TO WESTERN ELECTRIC COMPANY, INCORPORATED, OF NEW YORK, N. Y., A CORPORATION OF NEW YORK

SYSTEM FOR CAUSING IMPULSES TO CONTROL THE PRODUCTION OF IMPULSES OF DIFFERENT FREQUENCY

Original application filed September 17, 1925, Serial No. 56,855, Patent No. 1,708,954, dated April 16, 1929.

Divided and this application filed February 8, 1929, Serial No. 338,403.

The present invention relates to improvements in systems for causing impulses to generate and control the frequency of other impulses of different frequency.

5 An object of the invention is to cause a series of impulses of current to produce another series of impulses of different frequency.

A feature of the invention relates to a relay arrangement responsive to impulses delivered over a circuit at a given frequency 10 to set up in another circuit impulses of one-half that frequency.

This invention has been divided from the application of L. M. Potts, Serial No. 56,855, 15 filed September 17, 1925, which became Patent Number 1,708,954 on April 16, 1929. In the application mentioned there has been disclosed a multiplex voice frequency telegraph system whereby the ordinary equipment employed in telephone exchange systems may be used for the transmission of a large number 20 of telegraph messages, thereby providing ninety-six one-way signaling channels on a single circuit. The terminal apparatus comprises distributor mechanisms consisting of 25 first, second and third stage distributors.

The present invention relates to features of the second stage distributors comprising polar relays responsive to impulses delivered 30 over the first stage or third stage distributors (depending upon whether signals are received or transmitted) at a given frequency, to set up impulses of a different frequency in the second stage distributors.

35 The invention will now be described having reference to the accompanying drawing which shows schematically a relay arrangement constituting one embodiment of the invention.

40 At the left end of the drawing is shown one of a plurality of incoming signal channels 22 terminated in the alternating current relay 23. Six channels similar to 22 are each connected through a start-stop translating mechanism 42 to distributor 120. The distributor successively connects each of the six channels one at a time to line 416. Likewise distributor 130 successively connects four lines similar to 416 one at a time to 45 line 418. At the distant end (not illus-

trated) of line 418 a similar distributor 130 may be employed to distribute the signals from line 418 to a group of distributors 120 where the signals will be distributed to receiving lines.

Distributor 130 is controlled by relay 414 which is operated from a source of alternating current (not shown). Distributor 130 in turn controls distributor 120 through relays 7, 8, 9 and 10.

If desirable one of the channels may be devoted to synchronizing the distributors at each end of the line, in which the left contact of relay 1 of the distributor 120 would lead to a contact of switch 770 as shown by the 55 dotted line.

The alternating current relay 23 is designed to maintain its contacts normally closed and responds to current of a given frequency, such as 800 cycles per second, to open and hold open its contact during the time that current is flowing. Associated with the channel 22 is a start-stop translating mechanism 42 which, for the sake of convenience, have been illustrated schematically. This 60 start-stop mechanism includes a signal-receiving relay 43 which responds in the usual manner to open circuit conditions to cause the distributor 42, by means of the receiving magnet 44, to set up by mechanical means, 65 combinations representing the characters received. The start-stop translator 42 is associated with the relay distributor 120 by means of the circuit 45, which includes the start magnet 46 of the start-stop translator. The 70 circuit 45 is so connected to the distributor 120 that the magnet 46 is operated at a given point in the cycle of operation of the distributor 120 in order to start the start-stop translator at the proper instant.

The distributor 120 consists of twelve 75 counting relays 1 to 6 inclusive, and 121 to 126 inclusive. These relays are arranged to operate and lock in pairs, each pair causing the release of a preceding pair. The operating circuits are closed by the polarized relay 9. Relay 9 is in turn operated by relay 7, which is operated periodically by the distributor 130.

The distributing mechanism 130 consists 80

of four pairs of polarized relays 11, 12, 13, 14, 131, 132, 133 and 134, together with an operating relay 414 and a distributing relay 15. The relays 7, 8, 9 and 10, which are also polarized, serve to interconnect the distributing mechanisms 120 and 130. These relays are so arranged that their armatures always stay in the position in which they were last attracted; one winding serves to attract the armature in one direction, whereas the other winding serves to attract it in the opposite direction. The four pairs of relays 11, 131, and 12, 132 and 13, 133 and 14, 134 are arranged in counting relation to be operated from the contacts of relay 414.

Assume relays 11 and 131 and relays 12 and 132 are operated and the other relays of the selector are unoperated. Relays 13 and 133 operate and relays 11 and 131 release on the next step, and on the next succeeding step relays 14 and 134 operate and relays 12 and 132 release. This process continues as long as relay 414 receives impulses.

The relay 7 is arranged to operate through its lower winding whenever the upper windings of the second pair of relays of distributor 130, namely relays 12 and 132 are energized, and through its upper winding whenever the upper windings of the fourth pairs 14 and 134 are energized. In other words, the relay 7 operates once in each direction for every cycle of the counting relays 130. Relay 7, on closing its lower contact 2, charges the condenser 415 either with a positive or a negative charge depending upon the position of the armature of relay 8. When relay 7 next closes its upper contact 1, the condenser discharges through the windings of relays 8, 9 and 10, serving to operate these relays to their other positions. The effect of the alternate closures of contacts 1 and 2 of relay 7 and contacts 3 and 4 of relay 8 upon the periodicity of the impulses impressed upon the upper and lower windings of relay 7 and transmitted from relay 8 to relay 9 will now be considered step by step, reference being had to the table below for following the change of the position of the armatures through one cycle of operation.

	Initial position	Step a	Step b	Step c	Step d
55 Relay 7.....	/	\	/	\	/
Relay 8.....	\	/	/	\	/

60 Assuming the armatures of relays 7 and 8 in the position shown in the drawing, the condenser 415 will be charged with positive current from battery.

65 Step a.—On the next current impulse which for the position shown will be de-

livered by relay 12, the armature of relay 7 will reverse its position to make contact with contact 1. This will establish a current path from condenser 415 over contact 1 of relay 7 through the winding of relay 8. The condenser will discharge and the armature of relay 8 will be reversed to make contact with contact 4. The position of the armatures of relays 7 and 8 at the completion of this step is shown under "Step a" of the table.

Step b.—On the next current impulse, which will be delivered by the upper winding of relay 14, the armature of relay 7 is reversed to make contact with contact 2 and will assume the position shown. During this step the armature of relay 8 remains in the same position, that is, it still makes contact with contact 4; negative current flows from battery through contact 4 of relay 8 through the closed contact 2 of relay 7, and the condenser 415 will be charged with a negative charge. The position of the armatures of relays 7 and 8 at the completion of this step is shown under "Step b" of the table.

Step c.—On the next current impulse from relay 12 contact 1 will be closed. A circuit will be completed for the condenser and its negative charge will flow from condenser 415 over contact 1 through the winding of relay 8, reversing the position of its armature to make contact with contact 3. The position of the armatures of relays 7 and 8 at the completion of this step is shown under "Step c" of the table.

Step d.—On the next current impulse, which will be delivered by relay 14, contact 2 of the armature of relay 7 will be closed. The armature of relay 8 will remain in the same position, contact 3 being closed, thus permitting the current to flow from the positive battery to contact 3, contact 2 of relay 7 and the condenser will be charged with a positive charge.

This completes one cycle of operation of relay 8, its armature having returned to its initial position and being ready to be reversed by the next impulse received by relay 7, since the next impulse will reverse the armature of relay 7, thus discharging the condenser through the winding of relay 8 and reversing the position of its armature. During this cycle, the armature of relay 8 has been once on its contact 4 and once on its contact 3. During this one cycle of relay 8, however, the armature of relay 7 has described two complete cycles, i. e., it has been twice on its contact 1 and twice on its contact 2. From this it follows that the armature of relay 8 vibrates at one-half the frequency of relay 7.

Relay 8 operates in one direction during one cycle of the distributor 130, and in the other direction for the next succeeding cycle.

The relay 9 on each operation closes an operating circuit for a pair of counting relays

of the distributor 120. A frequency changer (not shown) is so connected to the polarized relay 414 that this relay is operated once in each direction for a complete cycle of the frequency changer, giving two operations of the relay 414 in 1/240th of a second. Since it is necessary for the relay 414 to operate four times to complete a cycle of the distributor 130, said distributor requires 1/120th of a second per cycle. Due to the manner in which the relay 7 is connected to the distributor 130, said relay operates once in each direction for each cycle of said distributor. Inasmuch as the relay 9 operates once for every two operations of the relay 7, it follows that each of the counting relays 1, 2, 3, 4, etc., of the distributor 120 requires two operations of the relay 7. Accordingly, for each cycle of the distributor 130, a pair of the counting relays 120 will be operated. This means that the distributor 120 requires 1/120th of a second per cycle.

All of the code impulses representing messages in the six channels leading to distributor 120 are directed through contacts of the relay 10, over conductor 416, to the contact of relay 11. In a similar manner, the impulses for three other groups of six lines each are directed over conductors 417 to the contacts of relays 12, 13 and 14, respectively. The armatures of these relays 11, 12, 13 and 14 are connected to the contacts of relay 15, whereby all impulses representing the messages in four different groups may be directed to the single conductor 418.

In order that the synchronizing impulses may be transmitted from the sending station to the receiving station for synchronizing the sending and receiving distributors, there may be provided a separate channel over which impulses may be transmitted simply for synchronizing purposes at the required time. If desirable, one of the channels shown may be devoted to synchronizing in which case the left contact of relay 1 of distributor 120 would lead to the contact of switch 770 as shown by the dotted line. After the distributors 120 and 130 at the sending station have been set in operation, the switch 770 may be closed to transmit the synchronizing impulses. Thereafter, each time the distributors 120 and 130 arrive at the proper relative phase relation with each other, a circuit is completed from ground through the switch 770 over the contact of relays 1, 10, 11 and 15 to line 418. At the receiving stations these impulses may be used to synchronize the receiving distributors.

What is claimed is:

1. In an electrical system, means for producing a series of impulses of current of one periodicity, a relay connected thereto having two pair of contacts, a source of current and a condenser for receiving and storing a charge from said source of current and a device actu-

ated by the discharge of said condenser all connected to said contacts whereby the charging of said condenser is effected by the closure of one of said pair of contacts and the discharge of said condenser is effected by the closure of the other of said pair of contacts. said device having switching means associated therewith which is connected to said condenser circuits, whereby the frequency of actuation of said device is one-half of the periodicity of 75 said impulses.

2. In a frequency changer, a condenser, two sources of current of opposite polarity, two polarized relays, one of said polarized relays having its armature connected to said condenser and adapted to have its armature vibrated by current impulses of a given periodicity to alternately charge the condenser from one or the other of said sources and to discharge the condenser through the winding of the second relay, the armature and contacts of said second relay being connected to the condenser charging circuit and the two sources of current so that the position of the armature of the second relay determines the polarity of the condenser charges in such a manner that the second relay is actuated at one-half the frequency of said first relay.

3. In a system for causing impulses to control the production of impulses of different frequency, a condenser, two electrical circuits, a polarized relay comprising a pair of contacts adapted to vibrate at the frequency of current impulses received by said relay to alternately open one and close the other of said two circuits, one of said circuits including said condenser and the winding of a second polarized relay and the other of said circuits including said condenser and two sources of differently polarized current, said second relay being adapted when traversed by a current impulse to close a circuit including one of said current sources and said condenser to charge said condenser with current of a polarity dependent upon the position of the armature of said second relay, whereby the discharge of said condenser through said second relay causes its armature to vibrate at a frequency one-half of that of the frequency of vibration of said first mentioned relay.

In witness whereof, I hereunto subscribe my name this 4th day of February, 1929.

LOUIS M. POTTS.
